(57) **CLAIM**

The ornamental design for a growth chart, as shown and described.

DESCRIPTION

FIG. 1 is a front elevational view of a growth chart;
FIG. 2 is a top plan view thereof, the bottom plan view being a mirror image thereof;
FIG. 3 is a right-side elevational view thereof, the left-side elevational view being a mirror image thereof;
FIG. 4 is a rear elevational view thereof; and,
FIG. 5 is an isometric view thereof, showing my design mounted to a doorjamb assembly.

The broken lines are for environmental purposes only and form no part of the claimed design.

The claimed growth chart, affixed to a doorjamb assembly, is used to measure a person's growth.
